UNITED STATES PATENT OFFICE.

PAUL SCHUYLER VAN BLOEM, OF HEMPSTEAD, NEW YORK, ASSIGNOR TO VIKING PRODUCTS CORPORATION, OF NEW YORK, N. Y., A CORPORATION OF NEW YORK.

ELEVATOR SIGNAL SYSTEM.

Application filed September 18, 1923. Serial No. 663,461.

To all whom it may concern:

Be it known that I, PAUL SCHUYLER VAN BLOEM, a citizen of the United States, and resident of Hempstead, in the county of 5 Nassau and State of New York, have invented certain new and useful Improvements in Elevator Signal Systems (Case No. 9), of which the following is a specification.

10 This invention relates to improvements in elevator signal systems, and has for its object to provide simple and efficient means for visually indicating at each floor served by an elevator car both the direction of 15 travel of the car and the position of the car in the elevator shaft; to provide means for indicating at each floor the position of an elevator car by means of an electric light mounted in a suitable sign box over 20 the usual shaft door at each floor and connected with the car to move back and forth to successively illuminate a series of signal compartments; and to provide elevator-car-controlled means for turning on a series of 25 "up" signal lamps and turning off a series of "down" signal lamps when the car reaches the lower limit of its travel, and turning off the "up" signal lamps and turning on the "down" signal lamps when the 30 car reaches the upper limit of its travel.

To the foregoing and other ends, which will hereinafter appear, the invention consists in the features of construction, arrangements of parts, and combinations of devices 35 set forth in the following description and particularly pointed out in the appended claims.

In the drawings:

40 Figure 1 is a vertical sectional view through an elevator shaft in a building equipped with the improved signal system;

Fig. 2 a front view showing the shaft door and signal box at one of the upper floors;

45 Fig. 3 a section on the line 3—3 of Fig. 2; Fig. 4 a section on the line 4—4 of Fig. 3;

Fig. 5 a section on the line 5—5 of Fig. 3, a part of the rear wall of the direction signal compartments being broken away;

50 Fig. 6 a section on the line 6—6 of Fig. 7;

Fig. 7 a sectional view similar to Fig. 3 taken through the signal box at the lowest floor served by the elevator car;

55 Fig. 8 a detail front view of the car-operated circuit-controlling means for the

direction signal lamps mounted in the signal box shown in Figs. 6 and 7; and

Fig. 9 a diagrammatic view showing the electric circuit for the car-position signal lamps and the direction signal lamps. 60

Referring to the drawings by numerals, 1 designates the elevator shaft in which the usual car 2 is raised and lowered by a hoisting mechanism 3 of ordinary construction. A belt 4 passes between a pressure roller 7 and a signal-unit driving roller 8 at each floor and is carried over pulleys 9 at the upper and lower ends of the shaft and secured at its ends to the front wall of the car 2 at 11. The pulleys 9 are 70 journaled on fixed bearings 12 suitably supported adjacent the front wall of the shaft 1, while the rollers 7 and 8 are journaled on bearings 10 and 13 respectively mounted in the shaft at the front wall thereof. The endless driving belt 4 preferably comprises a flat steel band which is adapted to drive the rollers 8 when the car moves, said band being clamped sufficiently tightly between rollers 7 and 8 to provide a non-slipping friction drive. It will be obvious that other suitable means such as a chain and sprocket drive might be substituted for this belt and friction wheel drive if desired. 75

80 Each driving wheel 8 has rigidly affixed to its rear face a pulley 14 connected by a driving belt 15 with a pulley 16 fixed on the rear end of a shaft 17 journalled in bearings 18 and 19 in the adjacent signal unit casing 20. The signal units at each 85 floor are precisely alike, except that the signal unit for the lowermost floor embodies certain additional devices for controlling the "up" and "down" signal lamps herein-after described. 90

95 Each signal unit casing is set in an opening in the front wall of the shaft 1 over the usual shaft door 21. The metallic casing 20 is of semi-cylindrical form and is closed at its front end by a metal face plate 23 and at its rear end by a metal back plate 24. Pulley 16 is located at the rear face of plate 24, and shaft 17 extends forwardly into casing 20 and has fixed thereon a worm 100 25 meshing with a worm gear 26. Gear 26 is fixed on a transverse shaft 27 journalled in bearings 28 in the casing 20, and said shaft has fixed thereon a worm 29 meshing with a worm gear 30. Gear 30 is fixed 105 on the rear end of a shaft 31 journalled in

bearings 32 and 33 in the casing and extends fore-and-aft within said casing. The worm gearing just described forms a reduction gearing for slowly oscillating shaft 31, said shaft being turned clockwise when the car moves upward and counter-clockwise when the car moves downward.

A radial arm 34 is fixed on shaft 31 adjacent the forward end of the shaft and carries at its outer end a forwardly extending metal cup 35 within which is housed an incandescent electric lamp 36 supported in a socket 37 carried by said arm.

The open front end of cup 35 is carried past the open rear ends of an arcuate series of car-position sign compartments 38, one for each floor served by the car, as the arm 34 is swung from side to side. The gearing above described is designed to swing the arm from the first to the last compartment 38 during travel of the car between the lowermost and uppermost floors served thereby. Compartments 38 are formed by radial portions 39 extending between two narrow concentric semi-cylindrical walls 40 and 41 rigidly mounted in casing 20 with their forward edges abutting the face plate 23. Plate 23 is cut away at the forward end of each compartment 38 in the manner of a stencil to form numerals designating the floors served by car 2 and glass blocks or sign characters 42 are secured by clips 43 against the rear face of said plate, said blocks having raised floor-designating numerals 42^a on their front faces projecting through the openings in the stencil plate 23.

The lamps 36 burn continuously while the car is in use, said lamps being wired in parallel as shown in Fig. 9, the filament of each lamp being located in a bridge F or transverse conductor line connected with line wires A and B leading, respectively, to the positive and negative terminals of a battery 44 or other source of current. A suitable manually operable switch 45 is provided at a convenient point, preferably adjacent the door 21 at the lowest floor served by the car, whereby the operator may break the circuit A—B—F when the operation of the car is stopped for the day.

In order that prospective passengers on any floor may ascertain whether a car is upward bound or downward bound at any time, even while the car is temporarily stationary at some point in the shaft, an "up" and a "down" signal is provided at each floor. To this end, each signal box casing 20 is provided with two closed direction-signal lamp compartments 46 arranged side by side within the front portion of said casing under the series of compartments 38. The compartments are enclosed by a semi-cylindrical wall 47, a rear vertical wall 48 located forward of the forward ends of shafts 17 and 31 a vertical fore-and-aft

partition plate 49, and the front plate 23 of the signal box casing 20. Plate 23 at the forward end of the left hand compartment 46 is cut away to form stencil apertures through which project the raised letters 50^a on a glass plate 50 held against the rear face of plate 23 by clips 51, said letters forming the word "up." The plate 23 at the forward end of the right hand compartment 46 is cut away to form stencil apertures through which project the raised letters 52^a on a glass plate 52 held against the rear face of plate 23 by clips 53, said letters forming the word "down." An "up" signal lamp 55 is mounted in the left hand compartment 46 and a down signal lamp 56 is mounted in the right hand compartment 46 said lamps being screwed in sockets 57 and 58 held to the bottom of casing 20.

Shaft 31 in the signal box 20 located at the lowest floor served by the car extends forwardly beyond bearing bracket 33 partly across the space between said bearing bracket and the rear wall 48 of the direction signal compartments. The three-arm rocking member 59 of a multiple-point car-controlled snap switch is loosely mounted on this projecting end of shaft 31 so as to be tilttable independently of the shaft. Said member 59 is formed of suitable insulating material and carries two switch contacts 60 and 61 adjacent the outer ends of its two laterally extending arms. These movable contacts 60 and 61 are both connected by a line wire A' with the positive pole of battery 44. Contact 60 is movable into and out of engagement with a fixed contact 62 supported on the casing 20 and suitably insulated therefrom, while contact 61 is movable into and out of engagement with a fixed contact 63 supported on and insulated from casing 20. Lamps 55 are wired in parallel with a line wire C leaking from contact and the negative line wire B of the car-position lamp signal circuit A—B—F, bridge conductors U connecting the terminals of the lamps 55 with lines C and B. Lamps 56 are connected by bridge conductors D with the negative line wire B and a line wire E leading to contact 63.

It will be obvious that when member 59 is rocked to the left to engage contacts 60 and 62 lamps 55 will be lighted, a circuit A'—C—U—B being thus completed through all the lamps and battery 44. At this time the circuit A'—E—D—B through lamps 56 will be broken due to separation of contacts 61—63. When member 59 is rocked in the opposite direction the circuit A'—E—D—B will be closed by engagement of contacts 61 and 63 and lamps 56 will be lighted while the circuit through lamps 55 will be broken by separation of contacts 60 and 62. A switch-operating block 64 of insulating material is rigidly held to arm 34 on shaft 31

at the forward side of said arm. The opposite side faces of block 64 are adapted to alternately engage the upper ends of the binding posts 60 and 61 on switch member 59 as the arm approaches the opposite limits of its travel and rock said member to shift the switch from one "on" position to the other "on" position. A spring 65 connected with the upwardly extending arm of member 59 and secured to a bracket 66 on casing 20 below the shaft 31 is shiftable across the front end of said shaft after a short preliminary rocking-movement of member 59 and serves to quickly complete the movement of said member from one "on" position to the other and hold it there. From the foregoing it will be obvious that the switch 59 will be automatically operated as the car reaches the lower limit of its travel to close a circuit through all the "up" signal lamps 55 and break a circuit through all the "down" signal lamps 56, while when the car reaches the upper limit of its travel said switch will be automatically operated to close the "down" signal lamp circuit and break the "up" signal lamp circuit.

What I claim is:

1. In an elevator signal system the combination of a plurality of dial plates for the different floors of a building served by an elevator car each dial plate having a series of floor designating characters thereon adapted to admit light through them, a movable lamp support located at the rear of each dial plate, an electric lamp carried by each support, an electrical circuit connected to all of said lamps and adapted to maintain them constantly illuminated during the up-and-down movements of the elevator car, and means operable by the movement of an elevator car from floor to floor for simultaneously shifting said lamp supports to move each lamp past the rear faces of the floor designating characters and thereby render the corresponding characters of each series luminous successively.

2. In an elevator signal system, the combination of a plurality of dial plates for the different floors of a building served by an elevator car each dial plate having a series of floor designating characters thereon adapted to admit light through them, a movable lamp support located at the rear of each dial plate, an electric lamp carried by each support, a closed electrical circuit connected to said lamps to maintain them constantly illuminated, means operable by the movement of an elevator up or down for simultaneously shifting said lamp supports to move each lamp back or forth past the rear faces of the floor designating characters and thereby render the corresponding characters of each series luminous successively, a pair of "up" and "down" signals con-

nected to each dial plate to indicate the direction of movement of the elevator car, an electric lamp to illuminate each signal, electric circuit means connected to all of the "up" signal lamps, electric circuit means connected to all of the "down" signal lamps, and means operated by one of said movable lamp supports at the limit of its movement in one direction to open the "up" signal circuit and close the "down" signal circuit and operated by said support at the limit of its movement in the opposite direction to close the "up" circuit and open the "down" circuit.

3. An elevator signal comprising a casing, an opaque dial plate closing the front of said casing, a pair of spaced arcuate concentric light-excluding walls of relatively slight depth extending rearwardly into the casing from the dial plate, the said plate being formed between the light-excluding wall with an arcuate series of stencil openings, a series of spaced light-excluding walls extending between the said arcuate walls and separating the different stencil openings of the series, a series of glass plates secured to the rear face of the dial plate in the enclosure formed by said light-excluding walls and formed with raised floor-designating characters projecting through the stencil openings and outwardly from the front face of the dial plate, a pair of glass plates secured to the rear wall of the dial plate within the arc of the floor-designating characters and formed respectively with the words "Up" and "Down" in raised letters projecting through stencil openings in the dial plate and outwardly from its front face, light-excluding walls arranged to form a pair of separate compartments within the casing back of said "up" and "down" plates, a lamp in each of said compartments, a radial arm pivoted at the rear of the dial plate in alignment with the center of the arcuate series of characters, a lamp carried by the outer end of said arm, and a light concentrating cup surrounding the lamp and carried by the said radial arm, said cup having its open end directly forwardly toward the floor-designating characters and disposed close to the rear edges of the light-excluding walls surrounding said characters, whereby the characters will be illuminated successively as the radial arm is swung.

4. An elevator signal comprising an opaque dial plate formed with an arcuate series of stencil openings, a series of glass plates secured to the rear face of the dial plate and formed with raised floor-designating characters projecting through the stencil openings and outwardly from the front face of the dial plate, a pair of glass plates secured to the rear wall of the dial plate within the arc of the floor-designating char-

acters and formed respectively with the words "Up" and "Down" in raised letters projecting through stencil openings in the dial plate and outwardly from its front face, a radial arm pivoted at the rear of the dial plate in alinement with the center of the arcuate series of characters, a lamp carried by the outer end of the radial arm, means carried by said arm to concentrate 10 the rays from said lamp and direct them forwardly at right angles from the arm and through the arc of the character series, a pair of fixed lamps located respectively back of the "up" and "down" signals to 15 illuminate them, and light-excluding walls arranged to surround said lamps and separate one lamp and its signal from the other lamp and its signal.

5. An elevator signal comprising a casing, an opaque dial plate closing the front of said casing, an arcuate series of floor-designating characters carried by the dial

plate and adapted to admit light therethrough, a radial arm pivotally mounted at the rear of the dial plate in alinement 25 with the center of the arcuate series of characters to swing in a plane parallel to the dial plate, a lamp carried by said arm, means carried by said arm to concentrate the rays from the lamp and direct them forwardly at right angles from the arm through the arc of the character series, a pair of "up" and "down" signals located in the dial plate within the arc of the character series and adapted to admit light through 30 them, a lamp located back of each signal to illuminate it, and light-excluding walls arranged to surround said lamps and separate one lamp and signal from the other lamp and signal. 40

In testimony whereof I hereunto affix my signature.

PAUL SCHUYLER VAN BLOEM.
